DESIGN FOR A COMBINATION BOTTLE AND CLOSURE CAP

Mae Joseph, Brooklyn, N. Y., assignor to Park &
Tilford, New York, N. Y., a corporation of New York

Application September 10, 1937, Serial No. 71,548

Term of patent 7 years

To all whom it may concern:

Be it known that I, Mae Joseph, a citizen of the United States, residing at 196 Rockaway Parkway, Brooklyn, county of Kings, and State of New York, have invented a new, original, and ornamental Design for a Combination Bottle and Closure Cap, of which the following is a specification, reference being had to the accompanying drawing, forming a part thereof.

In the drawing:—

Fig. 1 is a perspective view of a combination bottle and closure cap showing my new design.

Fig. 2 is a perspective view of the bottle with the cap removed.

Fig. 3 is a side view of the bottle with the cap removed.

I claim:—

The ornamental design for a combination bottle and closure cap, substantially as shown.

MAE JOSEPH.
